UNITED STATES PATENT OFFICE.

FOUNTAIN RAINWATER, OF WATERLOO, KENTUCKY.

SCREW-DRIVER.

SPECIFICATION forming part of Letters Patent No. 617,046, dated January 3, 1899.

Application filed March 12, 1898. Serial No. 673,648. (No model.)

To all whom it may concern:

Be it known that I, FOUNTAIN RAINWATER, a citizen of the United States, residing at Waterloo, in the county of Pulaski and State of Kentucky, have invented certain new and useful Improvements in Screw-Drivers, of which the following is a full and complete specification, such as will enable those skilled in the art to which it appertains to make and use the same.

This invention relates to ratchet screw-drivers; and the object is to provide a simple, cheap, and effective ratchet screw-driver of few parts and which is not liable to get out of working order.

The invention consists of a ratchet screw-driver constructed substantially as hereinabove described, and defined in the claims.

The invention is fully disclosed in the following specification, of which the accompanying drawings form a part, in which the separate parts of my improvement are designated by the same letters of reference in each of the views, and in which—

Figure 1 is a view in elevation of the improved ratchet screw-driver in its operative position. Fig. 2 is an enlarged sectional view of the upper end of the handle portion. Fig. 3 is a view of the inner side of the handle. Fig. 4 is a view in elevation of the upper portion of the bit. Fig. 5 is an end view thereof, and Fig. 6 is a sectional view of a detail.

In the drawings, A represents the handle portion of the improved ratchet screw-driver, which is preferably constructed of metal and is suitably shaped to adapt it comfortably to the hand, as is usual in such devices.

The handle A is preferably open at its central portion, forming, in effect, side bars, which are connected at the top and bottom by bands a a'. The lower band a' is provided with a central tubular bore a², within which is loosely housed the bit or shaft B. The upper band a is provided centrally upon its under side with a transverse groove a³, which terminates at each end in a socket a⁴ a⁵ of greater depth than the said groove a³. Upon the under side of the upper band a are arranged two beveled lugs or projections a⁶ a⁷, one, a⁶, of which is located adjacent to the socket a⁴ and the other, a⁷, adjacent to the socket a⁵. These lugs a⁶ a⁷ are beveled in op-

posite directions to each other, so as to present a sharp edge facing the front and the back face of the handle, forming ratchet-teeth 55 facing in opposite directions, as shown in Fig. 3.

The bit or shaft B is loosely sleeved in the tubular bore a² and is provided upon its side with a lug b, which bears upon the upper side 60 of the lower band a' and prevents the shank B from slipping through the tubular bore a². The upper end of the shaft or bit B is provided with an annular flange b', and above this flange is an upwardly-projecting pin b², 65 which is adapted to engage the groove a³ and is of sufficient length to be seated in either one of the sockets a⁴ a⁵. The upper face of the flange b' is provided with radial lugs b³, which are adapted to be engaged by the 70 ratchet-teeth a⁶ and a⁷. The lower end of the bit or shaft B is beveled to an edge to permit of its entrance into the slot of a screw-head.

It will be understood that any desired form of screw-grasping device may be applied to 75 the lower end of the shaft B, the form shown being chosen because of simplicity.

In operating the ratchet screw-driver above described the shaft B is forced upwardly until the pin b² is seated in one of the sockets 80 a⁴ a⁵. When in this position, upon turning the handle A in one direction the lugs b³ will be engaged by the ratchet-tooth a⁶ or a⁷ and the shaft B rotated. When the handle is turned in the reverse direction while the shaft 85 remains in the same socket, the ratchet-tooth will present only its beveled side to the lug a⁶ or a⁷ and slip by without rotating the shaft. The operation is the same when the shaft engages the other socket, except that the rotation of the shaft is the reverse of that just described. From this description it will be evident that a screw may be quickly and easily seated or withdrawn without the necessity of removing the shaft therefrom or of releasing the hold upon the handle. It is evident that the end of the bit might be provided with a wrench-socket and used as a nut-wrench.

Having fully described my invention, I 100 claim as new and desire to secure by Letters Patent—

1. A ratchet-tool, comprising a handle having a tubular bore at its lower end, said han-

dle being also provided with a longitudinal central opening, the end wall of which opposite the tubular bore is provided with a transverse groove at each end of which is a socket, said end wall being also provided at the opposite end of said transverse groove with ratchet-teeth which project in opposite directions, and a shaft which passes through said tubular bore in one end of said handle and which is provided at the end thereof within the handle with a disk having radial teeth on its outer side which are adapted to engage said ratchet-teeth and which is provided with a pin adapted to enter said sockets, substantially as shown and described.

2. A ratchet-tool, comprising a handle provided upon the upper end thereof with sockets arranged on each side of the center and connected by a groove, a ratchet-tooth arranged adjacent to each socket, the engaging faces of said ratchet-teeth being oppositely directed, the said handle having also a tubular bore in its lower end, a shaft loosely sleeved in said bore and having a pin at its upper end adapted to engage one of said sockets, an annular flange at the base of said pin and

provided upon its upper face with lugs adapted to engage said ratchet-teeth, substantially as described.

3. A ratchet-tool comprising a hollow handle constructed of two side bars and an upper and lower band, the said upper band being provided upon its under face with two sockets and a groove connecting said sockets, a ratchet-tooth arranged adjacent to each socket, the engaging faces of said ratchet-teeth being oppositely directed, the said lower band being provided with a vertical opening, a shaft loosely sleeved in said opening and having a pin at its upper end adapted to engage either of the sockets in the upper band, a flange arranged at the base of said pin and provided upon its upper face with lugs adapted to be engaged by the ratchet-teeth, substantially as described.

In testimony that I claim the foregoing as my invention I have signed my name in presence of the subscribing witnesses.

FOUNTAIN RAINWATER.
